UNITED STATES PATENT OFFICE.

CHARLES B. POST, OF NEW LONDON, OHIO, ASSIGNOR TO WARD & STILSON,
OF NEW LONDON, OHIO, A FIRM.

INITIATING APPARATUS.

SPECIFICATION forming part of Letters Patent No. 686,831, dated November 12, 1901.

Application filed July 29, 1901. Serial No. 70,083. (No model.)

To all whom it may concern:

Be it known that I, CHARLES B. POST, a citizen of the United States, and a resident of New London, county of Huron, State of Ohio, **5** have invented certain new and useful Improvements in Initiating Apparatus, of which I hereby declare the following to be a full, clear, and exact description, such as will enable others skilled in the art to which it **10** pertains to make and use the same.

My invention relates to improvements in initiating apparatus employed in conducting initiation services for secret societies; and it consists in the combination and arrangement **15** of the various parts and construction of the details, as hereinafter described, shown in the accompanying drawings, and specifically pointed out in the claims.

In the accompanying drawings, Figure 1 is **20** a plan view of the device with the platform removed. Fig. 2 is a longitudinal central section thereof. Fig. 3 is a detail of pivoted supporting-bar and projecting arms.

In the views, 1 is the stand, and 2 the plat-**25** form.

3 3 are transverse bars upon which the plat-**30**form rests.

4 represents projecting arms to which the bars are secured. These bars are pivoted eccen-**35**trically upon the sides of the stand 1 at 5.

7 represents bars pivoted at 8 upon one side of the stand and when placed in the vertical position, as seen in Fig. 2, support the extremities of the arms 4. These vertical bars are **40** connected by the link-bar 6, so as to move in unison. One of these bars 7 is extended below the edge of the stand at 9, where it will be accessible to the toe of the operator, so that by a slight push on the bar the arms will be disengaged and will fall, letting down the transverse bars 4, and the platform will fall **45**into the stand.

At the base of the stand is seen a cartridge-

holder 10, so placed that the inclosed cartridge will be struck by one of the arms 4, which is **45** provided with a point 11, arranged to engage a percussion-cap 12 on the cartridge and explode it, making a great noise, simultaneous with the fall of the platform. The height of the stand is not sufficient to injure any one **50** seated or standing thereon when they fall, but serves merely to give zest to the initiation services.

Having described my invention, what I claim as new, and desire to secure by Letters **55** Patent, is—

1. An initiating apparatus, comprising a stand, pivot-bars upon said stand and arms extending therefrom, a platform resting upon said bars, a tripping device for said arms and **60** a detonator arranged in the path of one of the falling arms, substantially as described.

2. In an initiating apparatus the combination with a stand, of bars transversely and eccentrically pivoted on said stand, arms projecting from said bars, vertically-placed bars supporting said arms and pivoted to said stand, one of said bars extending below the edge of the stand, a link connecting said vertical bars, and a platform mounted upon said **70** pivoted bars, substantially as described.

3. The combination with a hollow stand, of transverse bars eccentrically pivoted thereon, arms projecting therefrom, pivoted supports for said arms, a detonating device arranged **75** to be exploded by the fall of the said arms, and a platform mounted upon said transverse bars, substantially as described.

In testimony whereof I have signed my name to this specification in the presence of **80** two subscribing witnesses.

CHARLES B. POST.
